Inventor:

Edward Herbst, Jr.

United States Patent Office.

EDWARD HERBSTER, OF CHICAGO, ILLINOIS.

Letters Patent No. 89,762, dated May 4, 1869.

IMPROVEMENT IN ALARM-LOCKS.

The Schedule referred to in these Letters Patent and making part of the same.

To all whom it may concern:

Be it known that I, EDWARD HERBSTER, of Chicago, in the county of Cook, and State of Illinois, have invented an Improved Lock; and I do hereby declare that the following is a full, clear, and exact description thereof, reference being had to the accompanying drawings, and letters marked thereon, making a part of this description, in which—

Figure 1 is a perspective representation of my invention, as attached to the inside of a door.

Figure 2, a view of the inside with the back plate removed.

Figures 3, 4, 5, 6, the guard-plates of the bolt.

Figure 7, a perspective view of the bolt.

Figure 8, a transverse section of the bolt and guard-plates.

Figure 9, the key.

Figure 10, the ratchet-cylinder.

Figure 11, the stop which holds the guards in place, removed from the case.

The nature of the present invention consists in the novel construction and arrangement of a ratchet-key cylinder, which gives an alarm when the key is turned, and which, when locked by a spring-stop, holds the key in the hole.

A represents the case;

G, the spring-catch;

1, 2, 3, 4, the guards;

Q, the bolt; and

S, the guard-stop of an ordinary rim-lock, said guards being pivoted to a pin, R, and operated by the key Z in the usual manner.

L F, figs. 1, 2, and 10, represent the eye of the key-hole, which passes through the front and back plates of the case, and it is held in place by a flange, Y, and ratchet-wheel M, both of which are rigidly at-

tached to the eye, and rotate between the front and back plates of the lock, and are slotted out at E', to receive the nib of the key Z.

The ratchet M has a hole, P, made through it, in which a spur, or pin, E, put through the end of a spring, D, is placed to hold the eye L F in a fixed position, and it operates upon the end of a spring, K, fig. 2, and thus gives an alarm when the key Z is turned.

Operation.

To lock the door, put the end of the key into the eye L F, and so turn it around as to bring the slots E' opposite to the slot d in the case A, fig. 1, the end F projecting through the case far enough for this purpose. This will allow the key to enter the lock and turn the bolt Q.

To lock the key in the key-hole, turn it around until the hole P in the ratchet M is opposite the hole I in the case A; then swing the spring D on its pivot, until the pin E passes into the hole.

By means of this construction and arrangement a substantial alarm-lock is provided at small cost, while at the same time the key is so locked in the door, as to prevent it from being turned from the opposite side.

Having thus described my invention,

What I claim, and desire to secure by Letters Patent of the United States, is—

A lock, A, provided with a rotating eye-cylinder, F, flange Y, ratchet M, spring K, and spring-stop D E, so operating as to give an alarm, and hold the key in the lock, as set forth.

EDWARD HERBSTER.
